UNITED STATES PATENT OFFICE.

FRANK J. TUMA, OF RICHMOND, VIRGINIA.

WORK-SUPPORT FOR CHAIR-REPAIRING MACHINES.

1,122,442.

Specification of Letters Patent. Patented Dec. 29, 1914.

Application filed January 17, 1914. Serial No. 812,793.

To all whom it may concern:

Be it known that I, FRANK J. TUMA, a citizen of the United States of America, residing at Richmond, in the county of Henrico and State of Virginia, have invented 5 certain new and useful Improvements in Work-Supports for Chair-Repairing Machines, of which the following is a specification.

10 This invention relates to improvements in work supports for chair repairing machines.

In the art of cane seating chairs it is customary to be provided with a form of cane 15 fabric and the same is secured to the bottom member of a chair by providing the latter with an annular groove and securing the fabric stretched thereover by forcing and gluing a piece of bent wood into said 20 groove. The present invention is designed for the purpose of providing an advantageous method for supporting chair bottoms for cutting the said grooves when applying cane seat to old chairs and also for supporting chair bottoms for cutting the bent 25 wood strips and glue from the grooves in old chairs for the repairing of the same by recaning, or in other words while grooving and re-grooving old chairs of varying 30 shapes and sizes with their grooves at different distances from the edge of the seat.

The primary object of the invention therefore is to provide a work holder of the 35 present novel construction designed for accomplishing the above designated objects.

The invention consists in the novel combination and arrangement of parts herein-after fully described, illustrated in the accompanying drawings and pointed out in 40 the appended claims.

In the drawings forming a part of this application and in which like reference numerals designate corresponding parts throughout the several views: Figure 1 is a 45 front elevation of the device, portions of the work holder being broken away. Fig. 2 is a side elevation of the complete device. Fig. 3 is a detail view of one of the ends of the bracket member. Fig. 4 is a top plan 50 view of the work holder. Fig. 5 is a vertical central sectional view of the operating elements of the invention, and Fig. 6 is a detail plan view of the ratchet wheel employed therewith.

55 Referring more in detail to the drawings, it will be seen that wall brackets 10 are pro-

vided with a power shaft 11 journaled therein and revolved by the belt pulley 12, while a spur gear 13 upon said shaft meshes with the gear 14 upon the driven shaft 15 journaled in the cross members 16 and 17 of a frame 18 journaled at its upper end upon said power shaft 11.

The lower end of the frame 18 journals the tool stock 19 upon the ball bearings 20, 65 while the spur gears 21 and 22 carried respectively by the driven shaft and stock provide for a rotation of the latter. A circular saw 23 is removably secured in operative position to one end of said stock as 70 by the screw 24, while a bit or auger 25 is secured within a socket 26 in the opposite end of the stock by means of a set screw 27. Oil cups 28 are preferably provided communicating with the said bearings. A 75 forked brace 28' secured at one end to a permanent support is provided with a notch in the upper side of each of its bifurcated ends 28'' and adapted for the reception of the bolts 30 vertically slideable within the 80 slots 31 of the main frame 18 and retained in their adjusted positions by means of winged nuts. It will be evident that such a mounting of the frame 18 allows for the imparting of a pendulum motion thereto 85 upon its disengagement from the brace by loosening the nuts 32 and removing the bolts 30 from the notches 29. This also allows said bolts to drop to the bottoms of said slots 31 leaving a free swinging movement to the said frame. When desired to 90 rigidly retain the frame for active operations, the notches are brought into alignment with the slots 31 and the bolts placed within said notches and tightened in the 95 manner which will be evident.

Positioned directly beneath the above described mechanism there is provided the work holding device co-operating therewith which consists of the base member 32' retained in the stationary position by means of the locking devices 33 and having the upright tubular supporting shaft 34 mounted thereon. The work holding table 35 is provided with a central depending post 36 100 revoluble within the exteriorly threaded sleeve 37 screw-threaded into the boss 38 mounted for rotation upon the top of said shaft 34. For the purpose of elevating and lowering the table 35 it will be seen that the 105 boss is readily turned by means of the hand wheel 39 thereby feeding the threaded sleeve

37 with the table mounted thereon either upwardly or downwardly as desired, while said sleeve is prevented from rotation by means of the projecting pin 40 carried there-
5 by projecting through the vertical side slot 41 of the shaft. A circular top flange 42 is provided upon said sleeve and the ratchet teeth 43 upon its upper surface are adapted for engagement by the pawl 44 upon the
10 lower face of said table whereby a rotation of said table in a single direction is permitted.

The table 35 is provided with sliding encircling brackets 44 upon two of its oppositely projecting arms 45, while the other two arms 46 of said table are provided with slots 47 for the accommodation of blocks 48 slidably mounted therein and controlled by the turn screws 49 and so as to engage either 20 the outside or within the chair bottom for holding the latter. The arms 45 and 46 are independently rotatable, being both journaled upon the reduced end 36' of the post 36, with the arms 46 undermost and supporting said pawl 44'. A collar 50 upon said post 36 and revoluble therewith is positioned upon the annular untoothed portion 51 of said sleeve flange 42 and has the upper arms 45 and 46 mounted thereon.

30 In the operation of caning a chair seat by utilizing the present invention, the seat is clamped upon the table by means of the said block members, the table being readily turned in one direction by the hand of the
35 operator and its height regulated by turning the wheel 39. The circular saw 23 being set in motion by the described operative connections, it is evident that an annular groove of desired depth may be readily made in
40 the upper face of the work so clamped upon the table and if desired the table itself may not only be revolved but the saw frame may be slightly changed in position by a swinging movement imparted thereto as above described. The boring tool 25 operating horizontally may have the work upon said table moved into operative contact therewith as desired, for instance, in making dowel sockets in the chair seats which pass trans-
45 versely of the grooves made by the saw 23 and whereby the glued strips may be retained by means of dowels placed therein.

It is evident that the entire device now disclosed is necessary for the complete ac-
50 complishment of the designed objects, but it is nevertheless to be understood that minor

changes may be made in details of construction without departing from the spirit and scope of the invention as set forth in the appended claims.

What I claim is:-

1. A device of the class described comprising a base, a tubular shaft mounted thereon and having a longitudinal side slot, a boss mounted for turning upon the top 65 of said shaft, a sleeve screw-threaded within said boss, a projecting stud carried by said sleeve and adapted for sliding engagement within said slot, a four-armed table, a central post upon said table journaled within 70 said sleeve, ratchet teeth upon said sleeve and a pawl carried by said table adapted for engaging said teeth.

2. A device of the class described, comprising an upright tubular shaft having a longitudinal side slot, a boss mounted for turning upon the top of said shaft, a sleeve screw-threaded within said boss and extending interiorly of said shaft, a projecting stud carried by said sleeve and adapted for 80 sliding engagement within said slot, a post journaled within said shaft, a top flange upon said sleeve, an annular row of teeth upon the upper face of said flange, a collar upon said post revolvably seated upon the un- 85 toothed portion of said flange, and relatively shiftable arms journaled upon the top of said post.

3. A device of the class described, comprising an upright tubular shaft having a longitudinal side slot, a boss mounted for turning upon the top of said shaft, a sleeve screw-threaded within said boss and extending interiorly of said shaft, a projecting stud carried by said sleeve and adapted for 90 sliding engagement within said slot, a post journaled within said shaft, a top flange upon said sleeve, an annular row of teeth upon the upper face of said flange, a collar upon said post revolvably seated upon the 95 untoothed portion of said flange, two super-posed arms mounted upon said post above said collar and being independently rotatable, and a pawl adapted for engaging said teeth carried by the lower one of said arms. 100 105

In testimony whereof I affix my signature in presence of two witnesses.

FRANK J. TUMA.
